INVENTOR.

Austin M. Wolf.

UNITED STATES PATENT OFFICE.

AUSTIN M. WOLF, OF NEW YORK, N. Y., ASSIGNOR TO AMERICAN MOTORS CORPORATION, OF NEW YORK, N. Y., A CORPORATION OF VIRGINIA.

MIXING DEVICE.

1,182,954.

Specification of Letters Patent. Patented May 16, 1916.

Application filed May 13, 1912. Serial No. 696,927.

To all whom it may concern:

Be it known that I, AUSTIN M. WOLF, a citizen of the United States, residing at New York, in the county of New York and State of New York, and in the borough of Manhattan, have invented certain new and useful Improvements in Mixing Devices, of which the following is a specification.

My invention relates to mixing devices for fluids and is of particular use in connection with the fuel supply system of internal combustion engines, especially where a volatilized liquid hydrocarbon is used as part of the explosive mixture. A device for the same purposes and objects has been described by me in my copending United States patent application Serial No. 657,106.

The object of my invention is to provide a simple, indestructible, and compact device which will destroy the globular formation of the atomized hydrocarbon, coming from a carbureter or the like, before the same reaches the combustion chamber of the engine.

In the accompanying drawings forming part of this specification, Figure 1 is a perspective view of my mixing device; Fig. 2 is a plan view; Fig. 3 is a sectional view of the gas conduit, showing the mixing device in elevation; Fig. 4 is a view similar to Fig. 3, the mixing device in this case extending downward instead of upward from the pipe-coupling; Fig. 5 is a view similar to Fig. 2, but showing diagrammatically the movement of the particles of gas; Fig. 6 is a vertical section of the conduit, showing also the movement of the particles of gas; Fig. 7 is a plan view of a modified form of the device; Fig. 8 illustrates a modified form of the invention.

Referring to Fig. 1, the device consists of the tubular member 1 having the vanes 2 and 3. The number, shape and size of the vanes may vary, depending upon the process of manufacture, application of the device, etc. A flange 4 may be provided, as a means of holding the device in position, as shown in Fig. 3. The two members of the manifold, 5 and 6, are secured together, the joint being sealed by the gasket 8 and into which sinks the flange 4.

In Fig. 4, the flange 4 is provided at the top of the device, instead of at the bottom as shown in Fig. 3.

Figs. 1, 4, 5, 6 and 7 show the device in a form that will impart a right-handed whirl to the fluid or fluids passing through it.

Figs. 2 and 3, show the device adapted to impart a left-hand whirl. The direction of the whirling, one way or another, is immaterial.

In a preferable form of construction clearly shown in Figs. 2, 3 and 4, the vanes assume a steep angle with the axis of the tubular member 1 and present a flat surface to the passing fluid or fluids. The object of this construction, diagrammatically shown in Figs. 5 and 6, is to cause the globules of liquid hydrocarbon in the mixture to impinge forcibly against the wall of the fuel conduit. The impact shatters the globules, wherefore they are mechanically broken up.

Fig. 5 shows how the globules are directed against the wall because of the upward and abrupt deflection of the mixture caused by the steep, flat vanes.

Fig. 6 shows the globules entering the device, then being deflected so as to impinge on the wall of the conduit, whereby they are subdivided, in which state they more readily yield to the vaporizing influence of the air in the mixture because of the increased surface for the same mass. After the impact which is mostly tangential to the inner wall of the conduit, the mixture assumes a whirling motion whereby the whole charge is energetically mixed. As the spray nozzle of a carbureter, or similar device, is usually located in the center of the mixing chamber of the same, the liquid globules will tend to remain in the center or core of the fuel charge as it passes to the engine. To prevent such an occurrence, or to abort a stationary core in the mixture as it passes through the device, the vanes 2 and 3 in Fig. 2 are shown extending beyond the center of the device, overlapping, so that the vanes will cause an interference in the core of the fuel charge. The two center arrows, in the figure, show this result. The interference is then caught up by the main swirl and the whole charge thoroughly mixed.

Fig. 7 shows a modified form of the device, in which the inoperative portion of the tubular shell is removed, leaving but the vanes 2 and 3.

In Fig. 8, 18 is the conduit leading to the

engine. It is cut or slotted in such a manner so as to form the vanes 19. The member 20 incloses the conduit 18.

What I claim is:

5 1. A fuel-mixer comprising a tubular conduit with longitudinal slits in its upper portion and having each alternate edge of the portions between the slits bent inward to substantially the center of the conduit to 10 provide surfaces against which the gaseous mixture will impinge.

15 2. A fuel-mixer comprising a tubular conduit with longitudinal slits in its upper portion and having a part near each alternate edge of the portions between the slits bent inward to substantially the center of

the conduit to provide surfaces against which the gaseous mixture will impinge.

3. A fuel mixer comprising a tubular conduit longitudinally slit in its upper portion along two lines, and having each alternate edge of the portions between the slits bent inward to substantially the center of the conduit to provide two triangular surfaces against which the gaseous mixture 25 will impinge.

In witness whereof I have hereunto set my hand in the presence of two witnesses.

AUSTIN M. WOLF.

Witnesses:

WILLIAM BECKER,
EDWARD P. MURTHA.
